POST UNIT FOR ROOM DIVIDERS, GRILLES OR THE LIKE

Lewis S. Armento, Buffalo, N.Y.

Application October 8, 1957, Serial No. 48,008

Term of patent 14 years

(Cl. D13—1)

Fig. 1 is a front view of a post unit for room dividers, grilles or the like, embodying my new design.

Fig. 2 is a view of the right side thereof; the opposite or left side being similar in appearance but reversed.

Fig. 3 is a rear view thereof.

Fig. 4 is a top plan view of the member as shown in Fig. 2.

The central portion in Figs. 1, 2 and 3 is broken away to show indeterminate length of the post unit.

I claim:

The ornamental design for a post unit for room dividers, grilles or the like, substantially as shown and described.
